FOLDING CARD TABLE

Earl W. Edwards, Los Angeles, Calif.

Application November 27, 1936, Serial No. 113,062

1 Claim. (Cl. 311—87)

My invention relates to an improvement in folding card tables, such as are used for bridge, contract, and other games.

The object is to facilitate and expedite the folding of the legs out of the way, and to this end means is provided for folding two legs at a time rather than each of the four legs individually and separately.

My invention, therefore, consists in legs connected in pairs pivotally secured within the rim of the table top and at opposite sides thereof, together with means for simultaneously locking or unlocking the legs in pairs.

In the accompanying drawings:

Fig. 1 is a bottom plan view showing the table in folded position;

Fig. 2 is a fragmentary bottom plan view of one end of the table, showing parts of the legs as they would appear when folded;

Fig. 3 is a vertical longitudinal section of the upper portion of the table with the upper ends of the legs in the extended position and parts of the top broken out;

Figs. 4, 5, and 6, are enlarged fragmentary details in section and perspective.

The numeral 1 represents the table having the usual depending rim 2 extending all around the edges.

The legs 3 and 4 are connected together in pairs as shown in Figs. 1, 2, and 3, preferably by a tubular cross bar 5 by means of which they are rigidly secured together, and at opposite ends they are pivotally connected to the depending rim 2 of the table by pins 6 and 7. The tubular cross-bars 5 are located sufficiently away from the pivots to provide braces for and between the legs, and the better to lend rigidity thereto.

In the corners of the table are secured two forms of castings 8 and 9, and the pins 6 extend through the brackets 8, and pins 7 through the brackets 9. These two forms of brackets are only slightly different from each other. The brackets 8 are in the form of a right-angle like an angle-iron and fit two diametrically opposed angles of the table, and the brackets 9 are offset to form a recess 10, the purpose of which is to receive and hold within lateral bounds the two inner legs.

While various means might be employed for locking and unlocking these legs, both in the folded and open adjustments, one means only is herein disclosed and it consists in sliding bolts 11, which extend through guide blocks 12, in the outer ends of the tubular cross bars 5, and enter the openings in the form of notches 13, when the legs are extended as shown in Fig. 3. Connecting rods 15 extend inwardly from the bolts 11 to a lever 16, common to each pair of bolts, to which lever these connecting rods 15 are eccentrically pivoted at points 17, the lever being piv-

oted at its center on pin 18. A handle protrudes through a slot 20 in the tubular cross bar 5, by means of which the operator is able to move the lever in one direction, or the other, accordingly as he desires to lock or unlock the legs. A spring 21 coiled around one of the rods 15 is connected at one end to the tubular bar 5 (see Fig. 6), and at the other end to the connecting rod, as shown in Fig. 6.

All of these parts, namely, the bolts 11, connecting rods 15, lever 16, and springs 21 are conveniently housed in the tubular connecting bars 5, except the handles 19 which protrude through the slots 20 in the tubular connecting bar, in order to be accessible to the operator.

It is readily appreciated that with the foregoing type of table and construction, the legs are easily and quickly opened or closed by moving the handles 19 in the proper direction and by grasping two only of the legs from one side only of the table.

It may be readily understood that the legs of the table may be kept in their folded condition by the bolts 11, which at that time are flush on the inside of the bracket 8. The legs are adjusted tightly enough to prevent them from readily dropping out of place, and at the time that the table is to be set up for use it will be necessary only to grasp two of the legs and pull them from the table into the position in which they are shown in Figs. 3 and 4.

In this way, a very simple scheme is provided for fastening and unfastening, folding and unfolding the table, and locking and releasing the legs in pairs instead of individually, as has been the general custom heretofore.

Minor changes in details might be made within the range of my invention, and it is my object to cover and include these in the claim.

I claim:

The combination of a table top, brackets secured inside each corner, legs pivoted to the brackets, tubular cross-bars connecting these legs in pairs at a point some distance from the pivots, guide-blocks or plugs in the ends of the tubular cross-bars, sliding bolts extending through these guide blocks in position to enter openings in the brackets for holding the legs in open position, an operating lever pivotally mounted within the tubular bars and having a handle protruding through an opening in the bar, rods located within the tubular bars and extending from the bolts to the lever to which they are pivotally connected on opposite sides of the pivot of the lever, and a spring surrounding one of the rods and having one end secured to the rod and the other end to the tubular bar for normally sliding the bolts to a locking position.

EARL W. EDWARDS.
